(74) *Attorney, Agent, or Firm* — Brooks Kushman P.C.

(57) **CLAIM**

The ornamental design for a bakery tray, as shown and described.

DESCRIPTION

FIG. 1 is a top perspective view of a bakery tray according to an embodiment;

FIG. 2 is a bottom perspective view of the bakery tray of FIG. 1;

FIG. 3 is a top view of the bakery tray of FIG. 1;
FIG. 4 is a bottom view of the bakery tray of FIG. 1;
FIG. 5 is a right side view of the bakery tray of FIG. 1, the left side view being identical thereto;

FIG. 6 is front end view of the bakery tray of FIG. 1, the rear end view being identical thereto;

FIG. 7 is a top perspective view of a bakery tray according to another embodiment;

FIG. 8 is a bottom perspective view of the bakery tray of FIG. 7;

FIG. 9 is a top view of the bakery tray of FIG. 7;

FIG. 10 is a bottom view of the bakery tray of FIG. 7;

FIG. 11 is a right side view of the bakery tray of FIG. 7, the left side view being identical thereto; and,

FIG. 12 is front end view of the bakery tray of FIG. 7, the rear end view being identical thereto.

The broken lines in the drawings illustrate portions of the bakery tray which form no part of the claimed design.

1 Claim, 10 Drawing Sheets
